poration, a corporation of Delaware

Application October 28, 1944, Serial No. 560,828

12 Claims. (Cl. 89—140)

1

This invention relates to firearms, particularly to the type of firearm known as a carbine and disclosed, for example, in Patent No. 2,308,283 to Humeston. The invention is specifically concerned with the provision in such a weapon of means whereby it not only may be operated as a semi-automatic weapon but also selectively may be operated as a full-automatic weapon.

The basic carbines, of which the present invention represents an improvement, are characterized as gas-operated, self-loading, air-cooled shoulder weapons delivering semi-automatic fire controlled by the operator. The basic carbine is said to be semi-automatic in that when the trigger is operated rearwardly, assuming a round to be in the chamber, the hammer to be cocked and a reserve of ammunition to be in the magazine, a single shot is fired and thereafter the gun will automatically extract and eject the empty case, cock the hammer and chamber another round. The cycle may then be repeated by allowing the trigger to return to forward position and again moving it to rearward position.

The carbine of this invention may be fired semi-automatically as described in the immediately preceding paragraph, but upon throwing a selector arm may be operated fully automatically, that is to say, continuous fire may be delivered merely by holding the trigger in rearward position. Continuous fire may be interrupted by releasing the trigger and such fire will also cease upon exhaustion of the magazine.

It is, therefore, an object of this invention to provide a firearm selectively operable as a semi-automatic or full-automatic weapon. A further object is to provide a carbine of the type described in which, by the addition of a minimum number of simple parts, full-automatic fire may selectively be achieved. A further object is to provide alternate and additional parts for such a carbine which may readily be incorporated in the model now in service to modify it for selective full-automatic or semi-automatic fire.

With these and other objects in view, as will more fully appear, reference is had to the following description of one embodiment of the invention taken in connection with the accompanying drawings in which:

Figure 1 is a partial sectional right side view of a carbine embodying the invention as set for full-automatic operation and showing certain parts in firing position.

Figure 3 is a view similar to Figure 1 showing certain other parts in firing position.

Figure 3 is a view similar to Figure 2 showing

the parts immediately after the hammer has struck its blow.

Figure 4 is a view similar to Figure 3 showing the parts in another stage of cyclic operation.

Figure 5 is a left side view of a portion of the carbine.

Figure 6 is a section taken along the plane 6—6 of Figure 5.

Figure 7 is a view similar to Figure 1 showing the carbine set for semi-automatic operation, and

Figure 8 is an exploded view of the principal parts embodying the invention.

In the several views like reference characters refer to identical parts.

Turning now in particular to Figures 1 through 4 of the drawings, the carbine shown has a stock 1, containing the barrel and receiver group, the operating mechanism group, and the trigger housing group. A hand guard 2 overlies the rear part of the barrel with hand guard liner 3 in contact with the rear end of the barrel, the hand guard being secured to the stock by a front band (not shown) to unite the several groups into a whole.

The barrel and receiver group includes the barrel 4 which is provided with chamber 5 accommodating a round of ammunition having a cartridge case 6 and bullet 7. Affixed to the under side of the barrel is a gas cylinder 8 and at the rear of the barrel is affixed integrally therewith the receiver 9 having a raised portion 10 upon which is mounted the rear sight (not shown). At the extreme rear of the receiver is a lug 11 lockingly engaged in a recess formed in recoil plate 12 fastened to the stock by means of screw 13. The gas cylinder communicates with the bore of the rifle in conventional manner and is provided with gas piston 14 capable of limited reciprocal movement in the cylinder.

The operating mechanism group includes the bolt 15 having the usual firing pin reciprocable therein, the operating slide assembly 16, the operating slide spring 17 and the operating slide spring guide 18. The retracting handle 19, integral with the slide, is used for manually retracting the slide and bolt against resistance of spring 17. Under gas operation, piston 14 moves rearwardly, strikes the body of the operating slide and propels the latter in recoil in known manner against the force of the operating slide spring.

The trigger housing group includes the trigger housing 20 having an integral trigger guard 21. As best shown in Figure 1, the rear of the trigger housing is attached to the rear of the re-

ceiver by a T-shaped lug 22 on the housing which engages a corresponding recess formed in the lug 23 of the receiver. The forward end of the trigger housing is attached to the receiver by a pin 24 passing through upstanding ears 25 on the forward end of the housing and through depending lug 26 on the receiver (see Figure 6). A vertical opening 27 is provided by the forward part of the trigger housing for the reception of a magazine (not shown). A magazine catch 28 is positioned at the rear of the opening to engage the magazine to hold the same in the carbine.

Also included in the trigger housing group is the trigger 29 pivoted on trigger pin 30 fixed in the housing 20. A trigger spring 31 yieldingly urges and normally maintains the trigger in forward position as shown in Figures 1 and 2. A sear 32 is pivoted on the trigger pin 30 between arms 33 of the trigger. A hammer 34 is pivotally mounted on hammer pin 35 carried in the side walls of the trigger housing. A sear notch 36 is formed in the hammer to engage with the nose 37 of the sear for holding the hammer cocked as shown, for example, in Figure 2. The hammer spring plunger 38 seats in a notch 39 in the rear face of the hammer shank and the rear end of the plunger is loosely received in an aperture 40 in the rear of the trigger housing. Hammer spring 41 surrounds the shank of the plunger, seats in a counterbore 42 in the rear wall of the trigger housing and bears against a shoulder on the forward end of the plunger to urge the plunger forwardly and to rotate the hammer forwardly when released.

Received in suitable bores in the trigger and sear is sear spring 43 tending to tip the nose of the sear upwardly. The sear is provided with elongated slot 44 permitting limited longitudinal movement as well as tipping movement of the sear upon the trigger pin. The sear spring also urges the sear forwardly as shown in Figure 4.

The foregoing description of the parts of the carbine according to the invention would apply equally as well to the weapon illustrated by the aforementioned patent to Humeston and affords adequate basis for the immediately following explanation of the operation in semi-automatic fire of any of the carbines referred to.

Referring now to Figure 7 of the drawings there is shown the carbine of the present invention set for semi-automatic operation with the bolt closed and locked, the hammer cocked and the trigger in forward position. Assuming a round of ammunition to be in the chamber and a loaded magazine to be in position, the trigger 29 is moved rearwardly and pivots clockwise about the trigger pin 30. Sear seat 45 engages the underside of rear sear arm 46 tipping the latter upwardly, pivoting the sear on trigger pin 30 and depressing the nose 37 of the sear to disengage the nose from sear notch 36 of the hammer. Under influence of energy stored in hammer spring 41, hammer 34 is rotated forwardly to strike the firing pin in bolt 15 to fire the chambered cartridge. The firing cycle is so rapid that ordinarily the trigger is held in full rearward position until after completion of the cycle.

When the bullet has progressed beyond the port leading to the gas cylinder, bore gases under pressure enter the cylinder, move the piston rearwardly which, in turn, propels operating slide 16 to the rear against the action of operating slide spring 17. The rearward movement of the operating slide unlocks bolt 15 and moves the bolt

to the rear to extract the empty cartridge case and eject the same when it has cleared the breech. During rearward movement, the underside of the bolt engages the top of the hammer to rotate the same rearwardly and downwardly. The bolt and hammer are so related that the hammer, in rearward movement, overrides its cocked position allowing the nose of the sear to slide forward on trigger pin 30 under action of sear spring 43 and as permitted by the elongation of slot 44 to tip upwardly into the rearward extension of the sear notch 36. Such motion of the sear results in its taking a position with respect to the trigger substantially as shown in Figure 4, wherein the rear arm 46 of the sear rests in the depression 47 of the trigger and in front of the sear seat 45. Upon return of the hammer from overriding position to cocked position, the hammer, sear and trigger assume the attitudes shown in Figure 4 and the hammer is held in cocked position as the bolt is propelled forwardly by the operating slide 16 under action of operating slide spring 17. The bolt in its forward motion picks up and chambers a fresh cartridge and becomes locked to the barrel to complete the cycle.

It will be observed that, with the trigger back and the rear arm of the sear resting in depression 47 of the trigger, the sear cannot be tripped by the trigger until the latter has been released and allowed to spring forward as urged by spring 31 thus depressing sear seat 45 beneath sear arm 46 to clear the way for slight rearward movement of the sear to place the rear arm of the sear in position again to be engaged and tipped by the sear seat upon another pull of the trigger. Such rearward movement of the sear takes place under urge of hammer spring 41 as levered through the hammer 34, the sear notch 36 of which is engaged with the nose of the sear, to push the sear rearwardly on trigger pin 30 as permitted by elongated sear slot 44. The sear spring 43 yields to the rearward sear movement.

Keeping in mind the above description of the carbine and its operation in semi-automatic fire, there will now be described the additional parts provided in accordance with the invention for converting the carbine to a full-automatic weapon. Such additional parts comprise a sear trip 48, a sear trip lever 49, a selector crank 50, a selector 51, and a selector spring 52 (see Figure 8). It may here be remarked that certain of the parts common to the carbine of this invention and that of the aforementioned Humeston patent have been appropriately and slightly modified to accommodate the additional parts required for full-automatic functioning. Notably, the sear, hammer and operating slide have been so modified.

Sear trip 48 is pivotally carried by hammer pin 35 for limited rocking movement. The sear trip has a body portion 53, inturned sear tripping finger 54, plunger housing 55, and sear trip lever engaging arm 56. A sear trip plunger 57 is reciprocably carried in a cylinder formed in housing 55 and is backed up by a sear trip plunger spring 58 (see Figure 2). A vent 59 is provided in the bottom of housing 55 to prevent entrapment of air in the plunger cylinder and consequent sluggish plunger action.

Sear trip lever 49 has a pivot hole 60, rear arm 61, front arm 62 and upstanding terminal finger 63.

Selector crank 50 (Figure 8) has a pin 24, previously described in connection with the for-

ward mounting of the trigger housing and an integral crank arm 65, the latter having a sear trip lever pivot 66 integral therewith. The distal end of the pin 24 is notched on opposite sides at 67 to provide one element of a joint for engagement with selector 51.

Selector 51 is provided with slot 68 mating with the crank pin notches 67. It has a rising selector arm 69 and a rearwardly extending arm 70 having a recess 71 receiving the end of the selector spring 52. (Figures 2 to 4.)

Selector spring 52 is a simple bow-shaped spring provided at its rearward end with a loop 72 received in a recess in the trigger housing.

The selector mechanism and full-automatic parts, shown exploded in Figure 8, are shown assembled and in various stages of full-automatic operation in Figures 1 through 6. They are also shown in inactive positions in Figure 7.

As best seen in Figure 2, the sear trip 48 is pivoted on the hammer pin 35 adjacent the hammer. The sear trip lever is mounted on pivot 66 carried by selector crank arm 65 on selector pin 24 which, in turn, carries the selector 51 mounted on the opposite end of the pin. Selector spring 52 is shown in position, the forward end of the spring being received in the end of arm 70 and the rearward end of the spring being received in the trigger housing.

Figures 1 and 2 show the carbine ready to be fired. When the trigger is pulled, the rear arm of the sear is tipped up, as shown in Figure 3, and the nose of the sear is rotated out of the sear notch of the hammer to release the hammer for forward rotation. The sear then moves very slightly forward on the trigger pin until it comes to rest at 73 against the rear face of sear tripping finger 54 of the sear trip 48. Rear sear arm 46 still overlies the forward part of sear seat 45.

After the hammer has struck the firing pin and the bullet has progressed sufficiently far in the bore of the carbine to admit gas to the gas cylinder, as previously explained in connection with semi-automatic operation, the gas piston moves the operating slide 16 to the rear. The slide is provided with a downwardly facing cam, consisting of an upper forward horizontal surface 74, a rearwardly and downwardly inclined cam surface 75, and a lower short horizontal surface or dwell 76. Before the slide begins to move rearwardly, finger 63 engages the extreme forward part of the lower cam surface 76. During the first part of the slide's rearward movement, the tip of the finger is levered upwardly, by action of sear trip plunger spring 58 (Figure 2), as will presently be described, to follow inclined surface 75 and to cease upward rotation at a level adjacent upper cam surface 74. The first part of the rearward movement of slide 16 may be described as free movement, since it takes place prior to the rotational unlocking of the bolt, which latter begins substantially at the moment when the tip of finger 63 arrives at the upper cam surface 74.

As finger 63 rotates upwardly, the forward end of sear trip 48 is forced downwardly to the position shown in Figure 4 by action of sear trip spring 58 which bears against plunger 57 which in turn bears against a lower portion of the receiver 9. Sear trip lever engaging arm 56 is provided with a downwardly open slot 77 in which is received the end of rear arm 61 of the sear trip lever. Depression of rear arm 61 causes pivoting of the sear trip lever about pivot 66 thus causing

the tip of finger 63 to rise as permitted by the rearward recession of cam surfaces 76 and 75.

During travel of the operating slide and bolt to full rearward position, the usual extraction and ejection of the empty case occurs together with rearward rotation of the hammer. At the time in the operation when the hammer has just overridden cocked position under recoil of the bolt, as previously described, the sear is urged, by sear spring 43, fully forward on the trigger pin 30 and the rear arm 46 of the sear is tipped into the depression 47 of the trigger to assume the position shown in Figure 4. During such movement of the sear, the sear shoulder 73 slides under the raised sear tripping finger 54 and the sear nose is positioned high, so as to engage the sear notch of the hammer when the latter is freed of the bolt.

Thereafter, the bolt and operating slide move forwardly in counterrecoil, allowing the hammer to return to cocked position, picking up from the magazine a fresh round and chambering the same. Near the end of forward movement of the slide, the bolt is rotated to locked position, which rotation is completed just prior to engagement of the cam surface 75 with the tip of finger 63 of the sear trip lever.

The last increment of forward movement of the slide after completion of the rotation of the bolt to locked position is so called free movement, during which inclined surface 75 cams the forward end of the sear trip lever downwardly, pivoting the rear end of the lever upwardly. The forward arm of the sear trip 48 thus is pivoted upwardly and the sear tripping finger 54 is rocked downwardly against the top of sear 32 (Figure 4) to rotate the nose 37 of the sear out of the hammer sear notch 36 to begin a new cycle. It will be observed that the bolt is completely locked before the hammer can be released.

Subsequent cycles will be repeated so long as the trigger is held back and ammunition remains in the magazine. During such subsequent cycles, the sear is held forward on the trigger pin 30 by sear spring 43 when the sear is out of engagement with the sear notch of the hammer, and when in engagement with the sear notch is held substantially in forward position by the forward shoulder of the sear seat 45 abutting the rear end of the rear sear arm 46. During such cycles, substantially the only movement of the sear is the oscillating motion imparted downwardly by the sear tripping finger 54 and upwardly by the sear spring 43.

As stated, full-automatic fire may be stopped by releasing the trigger. The downwardly projecting portion of the lower side of the trigger snaps forwardly when released, after which the parts come to rest as shown in Figures 1 and 2, the sear having been levered back on the trigger pin by the hammer spring acting through the hammer and sear notch 36. In this position, when the slide returns to battery the sear trip finger 54 is depressed, as explained, but it does not trip the sear. Instead, this finger moves idly down in front of the shoulder 73 of the sear and stops in the position shown in Figures 1 and 2.

In Figure 7, and in dotted lines in Figure 5, there is shown the relationship of the parts when the selector arm 69 has been thrown rearward to position for semi-automatic fire. The two positions of selector arm 69 are best shown in Figure 5. The forward position (full lines) permits full-automatic fire and the rearward position permits semi-automatic fire. The top of arm 70 limits forward movement of the selector arm by abut-

ting the under surface of receiver 9. The bottom of arm 70 limits rearward movement of the selector arm by abutting an upper surface of trigger housing 20. The selector spring 52 yieldingly retains the selector arm in either of the two positions.

As best seen in Figure 6, and comparison of Figures 3 and 7, the motion of the selector arm is imparted to crank arm 65 and sear trip lever pivot 66 through pin 24. When the lever pivot 66 is in its lowest position, as seen in Figure 7, the sear trip plunger housing 55 is fully depressed and the sear tripping finger 54 is fully raised. Reciprocation of the operating slide now will not actuate the sear trip. The other parts of the carbine are thus free to operate semi-automatically as has been described, which is similar to the function of corresponding parts of the Patent No. 2,308,283 to Humeston.

It will be seen that there has been provided a firearm capable of either full-automatic or semi-automatic fire and in which the mechanism for tripping the sear in full-automatic fire is simple in construction and safe and positive in operation. As previously mentioned, the sear is not tripped until the bolt is closed and locked. Moreover, the sear is not tripped until the slide is substantially fully in battery, in which position the slide must be if the gas piston is to actuate the slide properly. The gas piston is limited in rearward movement to a short distance of about $\frac{9}{64}$ of an inch. The operating slide must be in contact with the gas piston during such limited movement of the latter in order that the slide may acquire sufficient momentum to be propelled to its rearward position. This condition is assured by providing appropriate cam surfaces on the slide itself and means coacting therewith to trip the sear in full-automatic operation only after the slide has substantially returned to battery. The cam recess 83 in the operating slide, by which the locking lug 80 of the bolt is rotated, is formed with a rearward terminal horizontal extension (open on the lower side of the slide) in which the lug 80 is received after completion of rotation of the bolt to full locked position, and the movement of the slide in counter recoil extends far enough to bring this lug into, and near the rear end of, the horizontal part of the recess 83 when the gas piston of the arm is fully pressed to it forward limit by the slide 16. The gas piston serves to limit the forward movement of the slide.

In order to attain maximum rapidity of automatic fire, the length of the sear trip lever arm 61 and finger 63 are so proportioned that the sear trip 48 is rotated a sufficient amount to operate the sear 32 to a let-off position just as the slide 16 abuts the gas piston. In practice, this let-off occurs when the finger 63 has been wiped by the upper half, or slightly more, of the inclined cam face 75. Thus, the angular movement of the sear trip 48 is such that its arm 54 engages the sear 32 to move the sear nose 37 out from under the trigger notch 36 just before completion of movement of the slide to battery position.

It should be noted that in moving the selector from "automatic-fire" position to "semi-automatic" position, the fulcrum represented by the pin 66 is not only lowered, tending to position the finger 63 below the cam faces 75-76, but is also moved forward, tending to position the finger 63 forwardly toward the forward limit of reciprocation of the cam face 75. Utilization of these two components of direction makes it possible to effect the change from semi-automatic to auto-

matic fire with a very small degree of movement of the selector.

The foregoing description is merely illustrative of the invention and is not to be considered as limitative. While the invention has been described with specific reference to carbines of the type illustrated by Patent 2,308,283 to Humeston, it will be understood that its principles may be applied to other firearms without departing from the spirit and scope of the invention as defined in the following claims.

We claim:

1. An automatic firearm comprising an operating slide; a breech bolt retracted by said slide upon recoil and returned to battery by said slide upon counterrecoil, said breech bolt extracting and ejecting an empty cartridge case upon recoil and chambering a fresh round of ammunition upon counterrecoil, a hammer pin, a hammer pivoted on said hammer pin and having an arcuate lower surface providing a sear notch, said hammer being cocked by said breech bolt upon retraction, a trigger pin, a sear pivoted upon said trigger pin, engageable in said sear notch and having an elongated pivot slot, a trigger pivoted upon said trigger pin, a sear spring between said sear and said trigger yieldingly urging said sear to a forward position in which the rear end of said sear slot abuts said trigger pin, said sear being movable to a rearward position against the action of said sear spring in which latter position the forward end of said sear slot abuts said trigger pin, a sear seat on said trigger trippingly engageable with said sear when the sear is in rearward position, a shoulder on said trigger engageable with said sear to hold said sear in forward position, a sear trip rockably pivoted on said hammer pin trippingly to engage a portion of said sear when said sear is in forward position, said sear having a recess into which said sear trip idly may rock when said sear is in rearward position, a pivoted sear trip lever having an arm for rocking said sear trip and having another arm, cam means on said slide slideably engaging said other arm to pivot said lever to rock said trip as said slide comes into battery, a movably mounted pivot carrying said sear trip lever, and selector means for moving said sear trip lever pivot to position the said other arm of said sear trip lever in inoperative position with respect to said cam means.

2. In an automatic firearm having a retractable bolt, an operating slide connected to the bolt, a hammer adapted to be cocked by the bolt, a trigger in operative relation to the hammer and a sear in operative relation to the trigger and hammer, the combination therewith of a member rockably pivoted adjacent the hammer and having a finger at one end extending transversely of the firearm and directed inwardly thereof and positioned to engage the hammer-engaging portion of the sear on rocking, said member having a finger at the other end also transverse to the firearm but extending outwardly thereof, a pivot pin, a lever medially pivoted to the firearm on said pivot pin and having one of its ends in engagement with the second mentioned finger and the other of its ends in engagement with the operating slide whereby the said second mentioned end of said lever is depressed when the operating slide is at the battery position, resilient means on the said second mentioned finger biasing the said first mentioned finger free of said sear when the said first mentioned end of said lever is freed for motion upon disengagement of

the said second mentioned end of the said lever from the slide, a crank arm attached to said pivot pin, stop means, a rockable means actuated between said stop means and secured to said crank arm for bodily adjusting said pivot pin whereby said lever is moved into or out of operative engagement with the slide, and spring means associated with said rockable means for holding the same against either stop means.

3. In an automatic weapon having a receiver, a slide reciprocably mounted on said receiver, a hammer oscillatively mounted in said receiver, a trigger pivotally mounted on said receiver and a sear tiltably mounted on said receiver adjacent the trigger and releasably engageable with said hammer, the combination therewith of a pin rotatably mounted in the receiver, a crank means mounted on said pin, a manually operable mounted selector arm positioned externally of said receiver and secured to said pin, snap acting spring means releasably retaining said arm in either of two limit positions, a first lever pivotally mounted on said crank means, a follower portion on said first lever adapted to be actuated by the slide, a second lever having a body portion pivotally mounted in the receiver, a sear tripping portion extending at a right angle from said body portion and operable in the plane of the sear, an abutment member extending from said body portion oppositely from said sear tripping portion and operable in the plane of the said first lever, an offset plunger housing on said body portion, and a spring pressed plunger in said housing adapted to abut said receiver, whereby in one limit position of said selector arm said first lever engages said abutment member upon actuation of said follower portion by the slide causing said sear tripping portion to trip said sear to release the hammer, and in the other limit position of said selector arm said first lever is inoperative to engage said abutment member to effect such release of the hammer.

4. In an automatic weapon having a receiver, a slide reciprocably mounted on said receiver, a hammer oscillatively mounted in said receiver, a trigger pivotally mounted on said receiver and a sear tiltably mounted on said receiver adjacent the trigger and releasably engageable with said hammer, the combination therewith of a first lever, a fulcrum means therefor in said receiver, a follower portion on said first lever adapted to be actuated by the slide, a second lever having a body portion pivotally mounted in the receiver, a sear tripping portion extending from said body portion and operable in the plane of the sear, an abutment member extending from said body portion and operable in the plane of the said first lever, a spring pressed plunger means in said body portion adapted to abut said receiver and means for adjusting said fulcrum means whereby in one position of the same the said cam follower portion is actuated by the slide causing said sear tripping portion to trip said sear to release the hammer, and in another position said first lever is inoperative to engage said abutment member to effect such release of the hammer.

5. In an automatic weapon having a receiver, a slide reciprocably mounted on said receiver, a hammer oscillatively mounted in said receiver, a trigger pivotally mounted on said receiver and a sear tiltably mounted on said receiver adjacent the trigger and releasably engageable with said hammer, the combination therewith of a first lever mounted on the receiver, a follower portion on one end of said first lever adapted to be actu-

ated by the slide, a second lever pivotally mounted in the receiver and having portions operable in the respective planes of the sear and said first lever for respective engagement therewith and means for bodily adjusting said first lever in the plane of motion of said first lever whereby in one position said follower portion is actuated by the slide for causing said sear to release the hammer and in another position of said first lever the same is inoperative to effect such release of the hammer.

6. In an automatic weapon having a receiver, a slide reciprocably mounted on said receiver, a hammer oscillatively mounted in said receiver, a trigger pivotally mounted on said receiver and a sear tiltably mounted on said receiver adjacent the trigger and releasably engageable with said hammer, the combination therewith of a first means movably mounted on said receiver for motion in a first plane, a follower portion on said first means adapted to be engaged and actuated by the slide, a second means mounted in the receiver for movement in a second plane parallel to said first plane and having a sear tripping portion and an abutment portion operable in the planes of the sear and said first means, respectively, and means supporting said first means for bodily adjustment from a first position in which said first means is movable by said slide to engage said second means to release said sear from said hammer, and a second position in which said first means is free of said second means for all positions of said slide.

7. In an automatic weapon having a receiver, a slide reciprocably mounted on said receiver, a hammer oscillatively mounted in said receiver, a trigger pivotally mounted on said receiver and a sear tiltably mounted on said receiver adjacent the trigger and releasably engageable with said hammer, the combination therewith of selector means manually operable into at least two positions, a first means mounted on said selector means and adapted to be actuated by the slide means, a second means having a body portion movably mounted adjacent the sear and adapted to trip the same, a sear tripping portion extending normal from said body portion, an abutment member extending from said body portion oppositely from said sear tripping portion, an offset plunger housing on said body portion, and a spring pressed plunger in said housing adapted to abut said receiver, whereby in one position of said selector means said first means is moved into operative engagement with said slide, to cause said sear tripping portion to tilt said sear to release the hammer and in the other of said positions of said selector means to render said first means inoperative to cause tilting of the sear tripping portion to effect such release of the hammer.

8. In a weapon having a receiver, a slide reciprocably mounted on said receiver and a sear tiltably mounted on said receiver, the combination therewith of an adjustable support on the receiver, a first means mounted on said support, a second means mounted on the receiver, said first means having portions operable in and engageable with the said second means and the slide, respectively, said second means adapted to engage the sear to tilt the same, and means for adjusting said support to shift bodily said first means either into or out of operative engagement with the slide whereby said first means will or will not, respectively, cause tilting of said sear.

9. In a gun having a receiver, a bolt recipro-

cable on said receiver, a slide reciprocable on said receiver to drive said bolt in one direction, a sear movably mounted on the receiver, the combination therewith of means on said receiver adapted to engage the sear for moving the same, an actuating means engaging said first named means and the slide whereby movement of the slide will effect movement of the sear, and means on the receiver for displacing bodily said actuating means relative to the slide whereby movement of the slide is ineffective to effect movement of the sear.

10. In an automatic firearm having a bolt, a gas operated reciprocable member engageable with said bolt to retract the same, and a spring-pressed hammer arranged to strike a firing member, a sear, means movably mounting said sear for engagement with said hammer to releasably secure said hammer in cocked position, a sear release member, means movably mounting said sear release member on said firearm in cooperative relation with said sear to move said sear out of engagement with said hammer, and an elongated link member having a pivot adjustable to bodily move said member, said member being operatively directly connected between said sear release member and said reciprocable member whereby movement of said reciprocable member to its battery position actuates said sear release member to release said sear from said hammer.

11. In an automatic firearm having a bolt and a gas-pressure operated reciprocable member engageable with said bolt to retract the same, in combination, a spring-pressed hammer arranged to strike a firing member slidably mounted by said bolt, a sear engageable with said hammer to secure said hammer in a cocked position, a sear release member movably mounted on the firearm and cooperating with said sear to move said sear out of engagement with said hammer, an elongated link movably mounted on the firearm longitudinally thereof, said link forming an operating connection between said sear release member and said reciprocable member, and means for selectively relating said link with said reciprocable member between a first position wherein said link is moved by said reciprocable member to contact and thereby operate said sear

release member only as said reciprocating member approaches its battery position and a second position wherein said link is out of contact with said reciprocable member for all positions of the latter.

12. In a weapon having a receiver, a slide reciprocably mounted on said receiver and a sear tiltably mounted on said receiver, the combination therewith, of a first lever means, sliding contact means on said first lever means and engageable by said slide to pivot said first lever means, a second lever means having portions thereof operable in the planes of said sear and said first lever means for engagement therewith, respectively, fulcrum means on the receiver pivotally supporting said first lever means, and manually operable means on the receiver for adjusting said fulcrum means between a first position wherein said slide engages said contact means to actuate said first lever means to cause tilting of the sear, and a second position in which said first lever means is clear of said slide for all positions of the latter.

FREDERICK W. SAMPSON.
PAUL H. HAMISCH.
